UNITED STATES PATENT OFFICE.

FRANK ROE BATCHELDER, OF WORCESTER, MASSACHUSETTS.

CARTRIDGE-BELT.

1,139,629.

Specification of Letters Patent.

Patented May 18, 1915.

Application filed March 29, 1911. Serial No. 617,655.

To all whom it may concern:

Be it known that I, FRANK ROE BATCHELDER, a citizen of the United States, residing at Worcester, in the county of Worcester, 5 State of Massachusetts, have invented a certain new and useful Improvement in Cartridge-Belts, of which the following is a specification, reference being had therein to the accompanying drawings.

10 The invention has relation to cartridge-belts, carriers, and other articles of woven material having pockets furnished with covers or flaps; more particularly, it relates to such as have a cover or flap made of a 15 separate piece of material. In the case of these last, the cover or flap usually has been combined with the pocket by inserting a portion of its length into the latter and attaching the inserted portion to the inner 20 surface of the back wall of the pocket by rivets, or stitches, or both. The inserted portion heretofore has ordinarily extended all the way to the bottom of the pocket, in order that the interior surface of the pocket 25 at the back of the latter may be smooth and free from any projection capable of obstructing the withdrawal of the contents of the pocket. The lower end of the inserted portion, if located at an intermediate point 30 in the height of the back wall, would constitute a projecting shoulder against which cartridges or clips would be likely to catch in being withdrawn from the pocket, especially if such end were doubled back 35 upon itself so as to turn the cut edge thereof in between the adjoining part of the said inserted portion and the back wall of the pocket, so as to conceal and protect the said cut edge. The inserted portion measures 40 ordinarily two or three inches in length; hence, the total length of the additional webbing that is required for the inserted attaching portions of the covers or flaps of all the pockets of a cartridge-belt is consider- 45 able and represents a considerable cost, adding largely to the expense incurred in the manufacture. Moreover, the additional webbing increases materially the weight of a cartridge-belt, which is a serious defect 50 from the military standpoint.

The invention provides for inclosing and housing the attaching portion of a cover or flap so that the lower end thereof is completely concealed and protected, and also 55 so that the formation of a sharply-defined shoulder liable to interfere with withdrawal

of the contents of the pocket is avoided. It obviates the necessity existing in the case of other constructions for extension of the inserted attaching portion of the cover or 60 flap to the bottom of the pocket, and permits the length of such portion to be considerably reduced so as to materially lessen the weight and reduce the cost. It also facilitates the process of manufacture. 65

In accordance with the invention, the pocket-wall to which the cover or flap is attached is woven for a portion of its depth in distinct thicknesses which are integral portions of such wall, and which for convenience I term plies, and is woven also with a slit between such thickness that admits the attaching portion of the cover or flap, whereby the said portion is housed between the plies, within the slit. The three 70 thicknesses of material are secured together in suitable manner, as by stitches or rivets, and thereby the attachment of the cover or flap is effected. The attaching portion requires to be inserted only far enough to 75 provide for firm attachment, the necessary extent being only a small part of the height of the pocket. The inner end of the attaching portion is completely inclosed, so that it is protected and concealed, and being external to the cartridge-receiving interior space of the pocket it does not constitute an obstruction within the pocket. The bottom of the slit constitutes an integral junction, 80 located above the bottom of the pocket, 85 which will limit the extent to which the inserted portion of the cover or flap is introduced. Much less care than heretofore required has to be exercised in inserting the 90 cover or flap-piece and adjusting it into 95 proper position, and it is easier to keep such piece in the required position while being attached. Therefore the operation of combining the flap or cover with the pocket and securing it permanently in place is more 100 readily and quickly performed, which contributes to reducing the cost of production. The length of the housing slit may be varied in different cases, according as it is deemed advisable to employ a narrow cover or flap 105 or a wide one, or to employ a cover or flap-strip having the attaching portion thereof of the same width as the main or covering portion of the strip or narrower than the latter portion.

In the drawings.—Figure 1 shows a portion of a cartridge-belt or carrier and illus-

trates certain of the principles of the invention. Fig. 2 is a view in vertical section in the plane of line 2, 2, of Fig. 1. Fig. 3 is a plan view of the pocket-web of Figs. 1 and 2 before the application of the flaps or covers thereto. Figs. 4, 5 and 6 are views similar to Fig. 1, illustrating different embodiments of the invention. Fig. 7 is a plan of a pocket-web woven with housing slits exceeding in length the width of a pocket. Fig. 8 shows a portion of a cartridge-belt or carrier made of a web on the order of that shown in Fig. 7. Fig. 9 is a plan view of a pocket-web having a continuous housing-slit. Figs. 10 and 11 are views each showing a portion of a cartridge-belt or carrier made of a web on the order of that shown in Fig. 9, with a separate cover or flap to each pocket. Fig. 12 is a view showing the application of a cover or flap extending over two pockets to a pocket-web on the order of that shown in Figs. 9 and 10. Figs. 13, 14 and 15 are views in vertical section illustrating other applications of the principles of the invention.

Having reference to the drawings, in the different figures of the drawings the respective pockets are marked A, and the portions of web which intervene between the pockets are marked B. The back walls of the respective pockets are marked 1, 1, etc. In Figs. 1 to 6, the upper portion of the back wall 1 is woven in the two distinct thicknesses of plies which are marked 1^a, 1^b, constituting integral portions of the said back wall, and between which plies is the housing slit. At both ends of each pocket and at the bottom of the slit the two thicknesses or plies are joined together in the weaving. In the embodiments of the invention which are shown in these figures the length of the two separate thicknesses or plies and the housing slit approximately equals the width of the pocket. The width of the cover or flap, C, of Figs. 1 and 2 is the same throughout as the length of the housing slit, and consequently is practically the same as the width of the pocket. The main or covering portion of the cover or flap, C', of Fig. 4 is wider than the portion c', thereof which is inserted into the housing slit. Consequently, the marginal portions of the said cover or flap project laterally at opposite sides of the pocket, so that when the cover is closed down into place such portions overlie and protect the side-portions of the pocket and its contents. The cover or flap C' may be woven with its attaching portion narrower than the main portion of the cover or flap, as shown in Fig. 4, or may be cut to the shape shown in the said figure. In each of Figs. 5 and 6, also, the cover or flap, C², C³, is wider than the pocket with which it is combined. The piece of material of which the cover or flap C² in Fig. 5 is made is of

uniform width throughout, but has the lateral parts c², c³, of its attaching portion turned inward upon the middle of such portion, to reduce the width of the latter, before insertion of the same into the housing slit which receives it. The cover or flap C³ of Fig. 6 is woven with a wide upper portion, a narrower lower portion, and tapering side-portions c³, c³, intermediate the wide portions and the narrower ones.

As will be apparent from Fig. 2, in applying the piece of material of which a cover or flap is composed, its attaching portion is simply pushed into the housing slit which has been provided for its reception, until its entering end touches the bottom of the slit. The cover or flap then is secured permanently to the pocket by means of stitches 3, and rivets 4, passing through the two plies and the attaching portion of the cover or flap, or by stitches alone, or by rivets alone.

The pocket-web may be woven in accordance with methods heretofore followed, with the addition of a sufficient number of warp-threads for producing an additional single ply, and with a proper modification of the interweaving of the weft with the warp-threads to produce the two plies one superimposed upon the other, the additional ply having a selvage and being of a proper width from its selvage to its junction with the other ply sufficient to afford the necessary cover for the cover or flap which is inserted between the two plies. In the case of those embodiments of the invention already described in which the additional ply extends only across the width of the pocket, the additional warp-threads may be interwoven with the other warp-threads and the weft into solid fabric at opposite sides of each pocket and between the successive pockets, or may be properly tied in at each side of a pocket and between the pockets be thrown to the back surface of the web and floated thereon, and subsequently cut away.

Advantages of the invention are illustrated in the case of the constructions shown in Figs. 7 to 12. In these constructions the length of the housing slit exceeds the width of the pocket, permitting of the employment of cover or flap-strips of the same uniform width throughout their length, and wider than a pocket. In Figs. 7 and 8 the top edge of the pocket-web is woven in two practically continuous plies 1^c, 1^d, which are tied together at a point, 1^e, midway between every two pockets by warp-threads crossing from one ply to the other. This construction allows a cover or flap-strip to be used which corresponds in width with the length of housing slit intermediate the crossing-over warp-threads at the point 1^e at one side of a pocket, and the point 1^e at the other side of such pocket. The covers or flaps of adjacent pockets may almost meet, edge to edge.

In Figs. 9 to 12 two plies 1^r, 1^g, and an intervening housing slit, extend continuously past two or more pockets, or an entire series of pockets of a cartridge-belt or carrier, and at each end beyond such pockets to the extent of a portion of an inch. This construction permits the employment of covers or flaps of uniform width throughout, and exceeding a pocket in width. Adjacent covers or flaps may meet, edge to edge, as in the case of the covers or flaps C⁵, C⁵, in Fig. 10, or may overlap each other as in the case of the flaps or covers C⁶, C⁶, in Fig. 11. The narrowing of the attaching portion of a cover or flap-strip, either in the weaving, or by turning or folding over, is rendered unnecessary. The continuous housing slit enables use to be made, when desired, of a cover or flap of sufficient width to cover two or more pockets, as at C' in Fig. 12.

Fig. 13 shows a form of embodiment in which the housing slit for the reception of the lower end of the cover or flap strip C⁸ is located intermediately of the height of the pocket. In this form an additional ply, 1^h, is woven upon the inner face of the back 1 within the pocket, with its lower portion connected with the back in the weaving, its upper edge being unconnected therewith so as to admit the said end of the said strip between the additional ply and the back. Stitches 3^a passing through the additional ply, the strip, and the back, secure the lower end of the strip in the housing slit between the two layers 1 and 1^h of material, and rivets 4 secure the strip to the back adjacent to the upper edge of the latter. The additional ply in this figure is located in the portion of the pocket which is occupied by the reduced mouth-ends and bullets of the cartridges which are placed in the pocket.

While this construction lacks somewhat the advantages in respect of reduced length of cover or flap-strip and of weight, which are possessed by the constructions that have already been described, the other advantages which are possessed by it are quite important.

Figs. 14 and 15 show constructions in which the slits are nearer the top of the pocket than in Fig. 10 but lower than in Figs. 1 to 9. In Fig. 14 the upper edge of the inner ply, 1^l, is at a short distance below the top edge of the back of the pocket, the stitches 3^b which pass through the said ply and through the lower portion of the cover or fly-strip C⁹ and the back being below the rivets 4 which secure the cover or flap-strip to the back adjacent to the top edge of the latter. In Fig. 15 the outer ply, 1^k, terminates a short distance below the top of the pocket and there are two lines of stitches, namely 3^c and 3^d, respectively below and above the rivets 4.

I claim as my invention:

A pocketed carrier woven with a pocket and having one of its web-portions woven for a portion of its depth in divided plies with an integral junction located above the bottom of the said pocket, and having combined therewith a cover-flap having its attaching end inserted between said plies and bottoming against said junction, and means engaging with the inserted portion and attaching the cover-flap to such web-portion.

In testimony whereof I affix my signature in presence of two witnesses.

FRANK ROE BATCHELDER.
